DESIGN FOR A COMBINED HOSIERY DISPLAY STAND AND SUPPORT

Irving Freilich, New York, N. Y.

Application August 10, 1939, Serial No. 86,588

Term of patent 3½ years

To all whom it may concern:

Be it known that I, Irving Freilich, a citizen of the United States of America, residing in New York city, in the Borough of Manhattan, county and State of New York, have invented a new, original, and ornamental Design for a Combined Hosiery Display Stand and Support, of which the following is a specification, reference being had to the accompanying drawing, forming part thereof, wherein:

Figure 1 is a perspective view of a combined hosiery display stand and support showing my new design.

Figure 2 is an enlarged perspective view of the support member thereof.

I claim:

The ornamental design for a combined hosiery display stand and support, substantially as shown.

IRVING FREILICH.
